UNITED STATES PATENT OFFICE.

WILLIAM H. HONIUS; OF HARTFORD, CONNECTICUT.

HERMETIC CLOSURE FOR RECEPTACLES.

No. 826,105.

Specification of Letters Patent.

Patented July 17, 1906.

Application filed March 21, 1904. Serial No. 199,220.

To all whom it may concern:

Be it known that I, WILLIAM H. HONIUS, a citizen of the United States, and a resident of Hartford, in the county of Hartford and State of Connecticut, have invented certain new and useful Improvements in Hermetic Closures for Receptacles, of which the following is a full, clear, and exact specification.

This invention relates to improvements in closures for the hermetic sealing of jars, tumblers, and other receptacles.

Figures 1 and 2 of the drawings are enlarged fragmentary side views in section of this improved closure as applied to a plain-rimmed tumbler arranged to seal against an outer zone of the tumbler-rim, Fig. 1 showing the parts in the position occupied by them during the air expelling or exhausting operation, while Fig. 2 shows the closure in its sealed position. Fig. 3 is a more complete side view, partially in section, of a tumbler with the gasket and cap in sealed condition. Figs. 4, 5, and 6 are views corresponding to Figs. 1, 2, and 3 and showing the parts arranged to seal the gasket against an inner zone of a plain tumbler-rim. Figs. 7 and 8 are fragmentary side views in section of this improved closure as applied to a shouldered jar, the two figures showing the parts in their unsealed and sealed condition, respectively.

This improved closure finds its chief utility in the form known as a "wedging" closure, in which the gasket is compressed at an angle against a peripheral edge or shoulder of a receptacle by means of a tapering or flaring cap. The gaskets most commonly used for these wedging closures are of circular or other compact cross-sections. These gaskets are supported prior to the sealing operation just above the shoulder or edge against which they are to be compressed, and it is necessary to deform a gasket of circular cross-section to a considerable extent from its original form in order to carry with certainty a sufficient amount of it across the sealing edge or zone of the receptacle upon which it is to be compressed. Inasmuch as the gasket should rest with comparative looseness upon its seat during the air-exhausting operation, it follows that the deforming of the gasket to carry it across its sealing-seat must take place during the sealing operation, which usually must be a very quick operation. Moreover, the sealing operation takes place 55 inside the hermetically-sealed retort and be-

yond the observation and direct control of the operator. Hence the safety and certainty of the seal when employing the customary form of gasket depend almost wholly upon the form and uniformity of the sealing-seat and the cap and upon the manipulative methods employed in the sealing operation.

The gasket used in this improved form of closure is particularly well adapted for use in the wedging type of closures, since it is comparatively thick at the middle portion, at which the principal pressure is applied, and thin toward the edges, where less rubber is required for the sealing operation. One of these thin edges is utilized to project across the sealing-seat while still in its initial or air-expelling condition, thus insuring a safe and certain positioning of the gasket as it is originally placed upon the receptacle by the operator, who is thus enabled to observe that each closure is in proper position for the subsequent sealing operation. Moreover, this form of gasket by disposing the material in the most advantageous manner effects an economy in the use of the rubber of which the gasket is made by reducing the cost of the material required for a given number of gaskets. The most suitable material now known for these gaskets is a high grade of rubber, which by reason of its increasing use in the arts is constantly increasing in value. Hence economy in its use is a factor of increasing importance.

The closure-gasket here shown is especially suited for the sealing of tumblers, mugs, or other receptacles having plain rims, which have heretofore been difficult to seal on account of having no supporting-shoulder for the gasket below the level of the rim of the jar, which shoulder has heretofore been regarded a necessity with the customary forms of gasket, especially for a wedging closure. Such shoulder, whether external or internal, unfits the receptacle for many subsequent household uses which might be served by a plain-rimmed receptacle, such as a tumbler or mug.

The present invention is therefore shown herein not only as applied to the sealing of a shouldered jar, but also as applied to the sealing of an ordinary glass tumbler, as a good example of a receptacle well adapted to a variety of household uses after its original purpose as a sealed package has been served.

The form of the gasket 26 used in this im-

proved closure is best shown in Fig. 1. The cross-section is approximately that of a parallelogram having oblique angles, the parallel inner and outer sides 27 and 28 of which are coincident with the inner and outer cylindrical faces of the gasket, respectively. The inclined line 30 of the cross-section is at an acute angle with the line 27 and is coincident with the exterior conical surface of the gasket, while the line 29 is inclined at an acute angle with the outer line 28 of the cross-section and is coincident with the inner conical surface of the gasket. More technically, the cross-section of this gasket is approximately that of a rhomboid or a rhombus the two opposite parallel sides of which are coincident with the cylindrical inner and outer faces of the gasket, which is, in effect, a short cylinder having oblique upper and lower edges. These oblique upper and lower edges are herein shown to be parallel with each other. Obviously the angle of obliquity may vary from that herein shown, and these two edges may also differ from each other as to the angle of obliquity. This gasket when of proper size will when placed upon the receiving-seat of a receptacle centralize and position itself in proper relation to the sealing-seat with the thin acute-angled edge 33 projected over and below the sealing-seat, as shown in Fig. 1. The edge 33 projects well below the outer edge of the rim 22 and between that rim and the cap-flange, thus bringing the thickest portion of the gasket approximately to the position at which it is to be wedged against the rim of the tumbler by the subsequent sealing operation. The thin edges of the gasket above and below the sealing portion thereof constitute safety margins for the gasket to insure the proper positioning of the thicker central or sealing zone of the gasket, the thinning of these edges effecting a saving of the material of which the gasket is composed, not only without sacrificing the efficiency of the gasket, but actually increasing that efficiency. The proportions of these gaskets and the angles of the respective edges may be varied to any desired extent to suit different receptacles or caps or to suit different conditions of service. The closure-cap employed in connection with these gaskets may be of different shapes, suited to the different types of receptacles on which the closure is to be employed. When employed for making a seal upon the outer edge of a receptacle, the cap may be of the form shown in Figs. 1, 2, 3, 7, and 8, the flange of the cap being flared outwardly toward its lower edge. In making the seal against an inner edge of a receptacle the form of cap may be as shown in Figs. 4, 5, and 6, in which the sealing portion of the flange flares outwardly at the top. In either case the cap is provided with a gasket-receiving seat, some portion of which is flared or inclined substantially in accordance with the oblique-angled face 29 and 30 of the gasket, this inclined seat being for the ultimate purpose of wedging the gasket at an angle against the receptacle-rim. The cap 41 (shown in Figs. 1 and 2) is provided with a flange of a generally flaring form, more specifically having an ogee flare instead of a straight flare. The inclined portion 42 is slightly curved; but it approximately conforms to the oblique face 30 of the gasket when resting loosely in the air-exhausting position shown in Fig. 1. Obviously, however, the inclined portion 42 of the cap 41 may be straight instead of being curved, or the oblique face 29 or 30 of the gasket may be slightly curved instead of being straight. The lower margin of the cap 41 below the inclined gasket receiving and sealing portion 42 is preferably adapted to engage with some portion of the cylindrical face 28 of the gasket, thereby aiding to centralize and retain the gasket in proper position relative to the cap.

The cap 45 (shown in Figs. 4, 5, and 6) is provided with an inclined gasket receiving and sealing portion 46, approximately coinciding with the oblique face 29 of the gasket 34. This cap is also preferably provided with an outer flange 47, extending approximately to or below the lower edge 35 of the gasket, which projects well below the inner edge of the tumbler-rim when resting in the air-exhausting position shown in Fig. 4. This closure is here represented as being adapted to wedge against the inside edge of a tumbler-rim. Therefore the gasket 34 is inverted from the position which it occupies when employed for outside sealing. (Shown in some of the other figures.) In Figs. 7 and 8 this gasket is shown as applied to the making of an outside seal on a jar 51, having a shouldered sealing-seat 49, which is preferably rounded or chamfered at the zone which is to receive the effective sealing pressure. The lower thin edge 52 of the gasket 48 projects across and below the shoulder 49 when resting in its initial or air-exhausting position, (shown in Fig. 7,) while the upper thin edge of the gasket extends between the flange of the cap 50 and the upper portion of the jar, thereby extending the supporting area of the gasket and the cap in their relation to the jar to aid in positioning them thereon before sealing without having an unnecessary and undesirable bulk or thickness of the gasket at its upper edge, the thinness of the edge permitting the cap to fit more closely around the upper portion of the jar. The receptacles employed in making these wedging closures are preferably provided with a more or less rounded or chamfered sealing-seat, upon which the wedging pressure of the gasket is received.

I claim as my invention—

1. The combination with a receptacle and a flaring cap, of a gasket made of rubber or

similar elastic material, and having a cylindrical face with an adjacent face forming an oblique angle therewith.

2. The combination with a receptacle and a flaring cap, of a gasket made of rubber or similar elastic material, and having inner and outer cylindrical faces and inclined edges.

3. A closure for hermetically-sealed receptacles comprising a gasket having an approximately cylindrical face and an adjacent face forming an oblique angle therewith, and a cap having a gasket-receiving seat, a portion of which is inclined in substantial accordance with the oblique face of the gasket.

4. A closure for hermetically-sealed receptacles comprising a gasket having inner and outer cylindrical faces, and an adjacent oblique face, and a cap having a gasket-receiving seat inclined in substantial conformity with the oblique face of the gasket.

5. A closure for hermetically-sealed receptacles comprising a gasket having an approximately rhombic or rhomboidal cross-section, the inner and outer faces of which are substantially cylindrical, and a cap having a receiving-seat, a portion of which is inclined in substantial accordance with one of the oblique angled faces of the gasket.

6. A closure for hermetically-sealed receptacles comprising a gasket having an approximately rhomboidal cross-section, the outer and inner faces of which are cylindrical and narrower than the oblique faces thereof, and a cap having a gasket-receiving seat, a portion of which is inclined in substantial accordance with one of the oblique faces of the gasket.

7. A closure for hermetically-sealed receptacles, comprising a gasket a cross-section of which is substantially a parallelogram having two shorter sides of cylindrical contour, and two longer sides at oblique angles with the shorter sides, and a cap provided with a receiving-seat, a portion of which is inclined in substantial accordance with an oblique face of the gasket.

8. The combination with a receptacle, of a hermetic sealing-closure, comprising a gasket having an acute-angled edge which projects at an inclination downwardly and across the sealing-seat of the receptacle, and a cap having an inclined sealing portion for wedging the gasket against the sealing-seat of the receptacle.

9. The combination with a receptacle, having a substantially rounded sealing-seat, of a gasket having an acute-angled edge which projects with a downward inclination across the sealing-seat of the receptacle, and a cap provided with an inclined portion, for wedging the gasket at an angle against the sealing-seat of the receptacle.

10. The combination with a receptacle having a substantially rounded sealing-seat, of a wedging closure therefor comprising a

gasket having inner and outer cylindrical faces and having an oblique-angled lower edge which projects with a downward inclination across the sealing-seat of the receptacle, and a cap provided with an inclined portion for wedging the gasket against the sealing-shoulder of the receptacle.

11. The combination with a receptacle having a rounded sealing zone, of a closure therefor, comprising a cap having a flexible flaring flange, and a gasket, the upper portion of which is smaller in diameter than the outer diameter of the receptacle-rim, and having lower faces which converge at an acute angle and project downwardly past the said rounded sealing zone of the receptacle.

12. The combination with a receptacle having a rounded rim, of a closure therefor comprising a cap having a flexible flaring flange and a gasket having upper faces which converge to a diameter smaller than the outer diameter of the receptacle-rim, and having lower faces which converge downwardly at an acute angle, and project through and beyond the annular space between the round of the rim and the cap-flange.

13. The combination with a receptacle having a substantially rounded sealing-seat, of a gasket having a cylindrical face, and an adjacent face at an oblique angle therewith, forming a wedge-shaped annular margin which projects downwardly and across the rounded sealing-seat of the receptacle, and a cap provided with a flexible flaring flange for compressing the said wedge-shaped portion of the gasket.

14. The combination, with a receptacle having a rounded rim, of a cap having a flexible flange, the upper portion of which is smaller in diameter than the outside of the receptacle-rim, and is inclined outwardly and downwardly, merging into a substantially cylindrical zone, larger than, and on the outside of, the receptacle-rim, and a gasket having a downwardly and outwardly inclined inner surface resting upon the outer portion of the rounded rim of the receptacle, and having an acute-angled lower annular corner extending into the annular space between the outer side of the receptacle-rim and the inner side of the cap-flange.

15. The combination with a receptacle having a plain rounded rim, of a hermetic closure therefor, comprising a gasket having a downwardly and outwardly inclined lower surface which in the uncompressed condition of the gasket rests upon the rounded rim, with an acute-angled annular corner projecting downwardly on the outer side of the rim, and a sealing-cap having a flexible flange which is inclined downwardly and outwardly, merging into a substantially cylindrical portion which extends downwardly upon the outer side of the receptacle-rim leaving an

annular space outside of said rim substantially less in width than the thickness of the gasket.

16. The combination with a receptacle having a plain rounded rim, of a sealing-closure therefor comprising a cap having a flexible flange, the upper portion of which is smaller in diameter than the outer diameter of the receptacle-rim, and which inclines outwardly and downwardly, merging into a zone having substantially vertical and parallel walls encompassing the outer side of the receptacle-rim, leaving an annular space of substantial width between them, and a gas-

ket having a downwardly and outwardly inclined lower surface resting upon the receptacle-rim, and provided with an acute-angled annular corner, which in the uncompressed condition of the gasket extends downwardly into the said annular space.

In testimony whereof I have signed my name to this specification in the presence of two subscribing witnesses.
